UNITED STATES PATENT OFFICE.

RUDOLPH F. STEHLIK, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

SWITCH-CONTROLLING DEVICE.

Application filed March 22, 1926. Serial No. 96,417.

This invention relates in general to automatic switch controlling devices such as are used on selectors, connectors, repeaters and the like; and the object of the invention, broadly stated, is the production of a self-adjusting relay for use on such controlling devices.

In ordinary telephone practice, automatic switches are supplied on a percentage basis, and are therefore made accessible to anyone of a plurality of lines or trunks and are controlled by current impulses sent over these lines or trunks. The length and characteristics of lines vary between wide limits, and for these reasons, the strength of the current impulses sent over the lines vary correspondingly.

For most satisfactory and reliable switch operation, however, the controlling devices must operate in a rather definite manner, and it is the object of this invention to introduce a switch controlling device which will operate in a definite predetermined manner, regardless of the length or characteristics of the line over which it is controlled. This is accomplished by providing the impulse receiving relay with an automatic spring-tension adjusting device which functions to adjust the tension of the retaining spring of the impulse receiving relay according to the characteristics of the particular line over which it is to be controlled.

The manner in which this result is accomplished may best be understood from a detailed description of the construction and the operation of this new automatic tension adjusting device, and also from a description of the operation of an ordinary impulse repeater utilizing this new device. Reference is had to the accompanying drawings, comprising Figs. 1, 2, and 3.

Fig. 1 is a plan view of the new automatic tension adjusting device and the impulse receiving relay and the release relay of an impulse repeater in conjunction with which the automatic spring adjusting device operates.

Fig. 2 is a front view of the above mechanism.

Fig. 3 is a schematic circuit diagram of an impulse repeater employing the new automatic tension adjusting device.

The construction of the new device will

first be described, referring to Figs. 1 and 2. The base 17 is the regular base upon which the various relays of the impulse repeater above referred to are mounted. The two relays shown in the drawings mounted on the base 17 are the ordinary line and release relays of the repeater, or as used on any automatic switching device. The line relay comprises the windings 11 wound on the core 64, the heel piece 10, armature 30, and the usual spring combination 15. Armature 30 also has an auxiliary extension arm 32, the purpose of which will become obvious in later descriptions. The release relay comprises the winding 13 wound on the core 65, the copper slug 61 on the upper end of the core, the heel piece 12, armature 31, and the spring combination 16. The spring combination 16 is provided with several extra springs; and to armature 31 a locking spring 35 is fastened by means of screws 36. The purpose of these additional springs will be described later.

The spring-tension adjusting mechanism proper comprises a field coil 2, having two windings and a C-shaped laminated iron core 3, the ends of which are shaped to form the pole faces between which the iron S-shaped armature 4 is positioned. A brass tie 6, fastened on one end to the heel piece 10 of the line relay by means of screws 14 and on the other end to the heel piece 12 of the release relay by means of screws 14', forms the mounting plate upon which the elements of the spring-tension adjusting device are mounted in operative relation to each other. The core 3 is fastened to tie 6 by means of four screws 7, which screw into the tie 6, and is held at a fixed distance from the tie 6 by means of the four spacers 8, through which the four screws 7 pass.

The S-shaped armature 4, the spacer 21, and the toothed wheel segment 20, are suitably fastened together and rotate as one member on the shaft 5. These three elements are kept in position on the shaft by means of the collar 22 secured to the shaft 100 by a screw. The shaft 5 is mounted on the tie 6 by means of the screw 9 which passes through the tie 6 and screws into the end of the shaft 5. The shaft 5 has an enlarged portion at the fastened end to form the side bearing face for the rotating mem-

ber and also to form a better shoulder to rest against the tie 6.

The curvature of the pole faces of the core 3 is cylindrical; the center of curvature 5 being the center about which the armature 4 rotates. The curvature of the faces of the armature 4 is such that, as the armature 4 moves in a clockwise direction, the air-gap between the pole faces and the armature 10 faces becomes smaller.

A pin 33 is riveted to the toothed wheel segment. This pin holds one end of the tension spring 34, the other end of which is looped through a small hole in the auxiliary 15 extension arm 32. The stop pin 37 is suitably fastened to the tie 6. Normally, the tension in spring 34 is relatively small, being sufficient to hold the armature 4 in its normal 20 position against the stop pin 37 and also to maintain the armature 30 of the line relay 25 in its normally released position. The free end of the spring 35 fastened to armature 31 is shaped to engage the teeth of the tooth wheel segment 20 and lock the armature 4 in position when the armature 31 of the release relay is actuated.

The operation of this device, and the function of the various elements of the device when used in an ordinary impulse repeater 30 will now be described. For this purpose it may be assumed that this repeater, the circuit of which is shown in Fig. 3, is accessible to a calling subscriber by way of one or more intervening automatic switches. It may further be assumed that a preceding switch has 35 been operated under the control of a calling subscriber and has extended a connection to the repeater shown in Fig. 3. When the repeater is seized, a circuit is closed for the line relay 11 and the field coil 2 in series which may be traced from ground through the lower winding of relay 11, lower winding of field coil 2, normally closed springs controlled by armature spring 45, bank contact 40, over the subscriber's talking loop to bank contact 38, normally closed springs controlled by armature spring 44, through the upper winding of field coil 2, through the upper winding of relay 11 to battery. The 45 current flow in the field coil 2 causes a magnetic field to be set up between the pole faces of the core 3. Due to this magnetic field, the armature 4, is rotated against the tension of spring 34 a distance proportional to the 50 strength of the current flow in the field coil 2. Since the field coil 2 is connected in series with the line relay 11, the tension in the spring 34 will be proportional to the strength of the current in the circuit over 55 which the impulses are to be sent. The line relay 11 also operates over the above traced circuit and closes the circuit for the release relay 13 at armature spring 46 and the working contact. Release relay 13 operates its 60 armature and causes the locking spring 35

to engage one of the teeth of the toothed wheel segment 20 and lock armature 4 in position. At armature springs 49 and 51, the upper and lower windings of the field coil 2 are short circuited, thereby deenergizing the field coil. The magnetic field between the pole faces of core 3 is destroyed, but the armature 4 is now held in position by means of the locking spring 35, and will be held in position until the release relay 13 70 is released, which takes place responsive to the replacement of the receiver by the calling subscriber, as will be described below.

As a further result of the operation of the release relay 13, at armature spring 48 80 ground is supplied to the holding conductor connected to bank contact 39 for holding up the precedingly operated switches in the usual manner. A circuit is also closed for the polarizing winding of the reversing relay 41 connected to this conductor. When relay 11 is energized, a bridge is also closed across the outgoing conductors 58 and 60 at armature spring 47, which includes impedance 43 and the upper winding of relay 90 41. This causes the preparation of the switch terminating the conductors 58 and 60 to receive the next series of impulses in the well known manner.

When the calling device at the calling substation is operated for this next digit, the circuit of the line relay 11 is opened a corresponding number of times. When relay 11 falls back, a circuit is closed for the slow acting relay 42 which disconnects the initial 100 bridge including the upper winding of the reversing relay 41 and the impedance 43 across the conductors 58 and 60, and substitutes a direct short-circuiting bridge therefor. The bridge across the conductors 58 105 and 60 is interrupted, however, at armature spring 47 each time relay 11 is deenergized, producing impulses which operate the succeeding switch. Since the tension of spring 34 has been adjusted corresponding to the 110 current strength in the energizing circuit of relay 11, the impulses repeated to the succeeding switch will be of the character to insure most reliable switch operation.

At the end of this series of impulses, line 115 relay 11 again remains energized causing the deenergization of relay 42 to replace the initial bridge across conductors 58 and 60, which has remained energized throughout the sending of current impulses due to its 120 slow acting characteristic. Release relay 13 likewise being slow acting remains energized continuously. In a similar manner the remaining series of impulses are transmitted over the outgoing trunk line comprising conductors 58 and 60 to establish a desired connection in the well known manner.

When the called subscriber removes his receiver to answer the call, the direction of current flow in conductors 58 to 60 is re- 125 130

- versed in some manner such as by a reversing relay in the final switch. The reversal of current in the upper winding of the reversing relay 41 causes the operation of relay 41. This reverses the direction of current flow over the conductors connected to bank contact 38 and 40 and may initiate any desired operation such as operating a meter or a signal.
- When the conversation is terminated, the subscribers will replace their receivers. The placing of the receiver at the calling substation opens the circuit of relay 11, which deenergizes and opens the circuit of the release relay 13. Release relay 13 deenergizes and causes the disengagement of spring 35 from the toothed wheel segment 20, thereby permitting the armature 4 to restore to its normal position under the tension of the spring 34. At armature spring 48, ground is removed from the holding conductor connected to bank contact 39. The removal of ground from the holding conductor opens the circuit of the lower polarizing winding of the reversing relay 41, and permits the release of the preceding switches in the well known manner. At armature springs 49 and 51, the short circuit placed around the windings of the field coil 2 is removed. The release of armature spring 47 also opens the bridge across the outgoing conductors 58 and 60 and permits the release of the succeeding switches in the well known manner.
- From the foregoing description, it will be seen that a device has been devised which automatically adjusts the spring tension on the impulse receiving relay in proportion to the current strength of the impulses to be received. The armature of the line relay operates the same regardless of whether the impulses received are weak or strong, and therefore will operate in direct synchronism with the calling device producing the impulses and will repeat impulses of the same character, which insures the most reliable switch operation. For example, if the repeater be taken for use to be operated over a very long line, the current in the field coil will be comparatively weak, and armature 4 will be rotated only a small amount, if any at all, thereby increasing the tension in spring 34 only a little. The line relay 11 will then respond to the comparatively weak current impulses in the desirable manner. If the repeater be taken for use to be operated over a very short line, the current in the field coil will be comparatively strong, and armature 4 will be rotated proportionately, thereby increasing the tension in spring 34 correspondingly. The increased current strength of the impulses will be balanced by the increased tension in spring 34. Again the line relay 11 will respond to the current impulses in the same desired manner. It is evident that this new device not only adjusts the spring tension of the line relay to compensate for the length of the line over which it is to operate, but also compensates for leakage between the two line conductors, or leakage of either line conductor to ground. While this spring tension adjusting device is shown used in a repeater, its use is not limited thereto. The arrangement shown here may be employed on any kind of an automatic switching device that must repeat impulses to a succeeding switch or to its own operating magnets.
- What is thought to be new and is desired to have protected by Letters Patent will be specifically stated in the appended claims.
- What is claimed is:
1. In an impulse repeating device, an impulse receiving relay, a restraining spring for the armature of said relay normally under tension, and means for automatically increasing the tension of said spring to any one of a plurality of values, the particular value in any case being in accordance with the current strength of the impulses to be received by said relay.
  2. In an impulse repeating device, an impulse receiving relay, a restraining spring for the armature of said relay, a field coil for producing a magnetic field, a rotating element mounted in said field, and a tension spring fastened to the armature of said relay and to said rotating element, said rotating element being so shaped that the amount of its displacement under the influence of the magnetical field produced by said field coil is directly proportional to the value of the current strength in said field coil.
  3. In an impulse repeating device, an impulse receiving relay, a restraining spring for the armature of said relay, a field coil for producing a magnetic field, a rotating element mounted in said field, a tension spring fastened to the armature of said relay and to said rotating element, said rotating element being so shaped that the amount of its displacement under the influence of the magnetical field produced by said field coil is directly proportional to the value of the current strength in said field coil, a second relay under the control of said impulse receiving relay, and a locking arm controlled by said second relay for locking said rotating element in a rotated position.
  4. In a self-adjusting relay, having a restraining spring for the armature of said relay, means for adjusting automatically the tension of said spring to any one of three values in accordance with the value of the current passed through the coil of said relay.
  5. In a self-adjusting relay having two energizing windings, an armature, and a restraining spring for said armature, means for energizing the two windings under varying tension.

- ing circumstances such that the values of the current in the two windings may or may not be the same, means automatically operative when current is passed through said two windings for adjusting the tension of said spring in accordance with the sum of the values of said current in the two windings.
6. In an impulse repeating device, an impulse receiving relay, a restraining spring for the armature of said relay, and means for automatically changing the normal tension of said spring in accordance with any one of a plurality of different values of the resistance of the circuit over which impulses 10 are to be transmitted to said relay.
7. In an impulse repeating device, an impulse receiving relay, a restraining spring for the armature of said relay, and means for automatically adjusting the tension of said spring prior to the reception of impulses by said relay in accordance with the current strength at which impulses are to be received.
8. In an impulse receiving device, an impulse receiving relay, a restraining spring for the armature of said relay, and a spring tension adjusting device for variably adjusting the tension of said restraining spring automatically operable when the said relay 20 is energized.
9. In an impulse receiving device, an impulse receiving relay, a restraining spring for the armature of said relay, a spring tension adjusting device for variably adjusting the tension of said spring, means for operating said device automatically when said relay is energized, the extent of operation depending upon the current strength in the winding of said relay.
10. In an impulse receiving device, an impulse receiving relay, a restraining spring for the armature of said relay, a spring tension adjusting device for variably adjusting the tension of said spring, means for operating said device automatically when said relay is energized, the extent of operation depending upon the current strength in the winding of said relay, and means for locking said device in an operated position independent of said operating means.
11. In a self-adjusting relay having a restraining spring for the armature of said relay, a spring-tension adjusting device for variably adjusting the tension of said restraining spring, and means for operating said device automatically when said relay is energized.
12. In a self-adjusting relay having a restraining spring for the armature of said relay, a spring tension adjusting device for variably adjusting the tension of said restraining spring, a circuit for energizing said relay, and means for operating said device automatically when said circuit is closed.
13. In a self-adjusting relay having a re- straining spring for the armature of said relay, a spring tension adjusting device for variably adjusting the tension of said restraining spring, a circuit for energizing the coil of said relay, means for operating said device automatically when said circuit is closed, the extent of operation of said device depending on the resistance of said circuit.
14. In a self-adjusting relay having a restraining spring for the armature of said relay, a spring tension adjusting device for variably adjusting the tension of said restraining spring, a circuit for energizing the coil of said relay, means for operating said device automatically when said circuit is closed, the extent of operation of said device depending on the resistance of said circuit, and means under the control of said relay for locking said device in position independent of said operating means.
15. In combination, an impulse repeating relay, and means for automatically adjusting said relay so that the ratio of the time of current flow to the time of no current flow 90 of the retransmitted impulse is the same as that of the received impulses, regardless of the variations of the current strength of the received impulses caused by the differences in the electrical characteristics of the lines 95 over which the received impulses are sent.
16. In combination, an impulse repeating relay, and means for automatically adjusting said relay so that the ratio of the time of current flow to the time of no current flow 100 of the retransmitted impulses is the same as that of the received impulses, irrespective of the resistance of the line over which the received impulses are produced.
17. In combination, an impulse repeating relay, and means for automatically adjusting said relay so that the ratio of the time of current flow to the time of no current flow of the retransmitted impulses is the same as that of the received impulses, irrespective of 110 the electrical characteristics of the line over which the received impulses are received.
18. The combination, with a relay adapted to be energized over lines varying in resistance, of means for automatically adjusting the relay each time it is energized in accordance with the resistance of the particular line over which it is energized, and separate means for maintaining the adjustment during the time the relay is energized over one 115 particular line.
19. The combination, with a relay adapted to be energized over lines having different electrical characteristics, of means for automatically and variably adjusting the relay 125 each time it is energized in accordance with the electrical characteristics of the particular line over which it is energized.
20. The method of correctly repeating impulses which consists in adjusting the re- 130

peating relay to the line over which the impulses are received and in readjusting the relay each time it is associated with a different line, so that the relay may be operated properly over lines of varying electrical characteristics.

21. The method of accurately repeating impulses in which a repeating relay is adapted to be operated over lines of varying electrical characteristics, which consists in adjusting the operating characteristics of the relay each time it is used in accordance with the electrical characteristics of the line over which it is to be operated.

15 22. In an impulse receiving device, an impulse receiving relay, a restraining spring for the armature of said relay, a spring tension adjusting device for adjusting the tension of said restraining spring operable in 20 the circuit of said relay, and means for disconnecting said device from the circuit of said relay after it has operated.

23. In an impulse receiving device, an impulse receiving relay, a restraining spring for the armature of said relay, a spring tension adjusting device for adjusting the tension of said spring, and means for operating said device when said relay is energized, the extent of operation depending on 30 the character of that energization.

24. In an impulse receiving device, an impulse receiving relay, a restraining spring for the armature of said relay, a spring tension adjusting device for adjusting the tension of said restraining spring, and means for variably operating said device in accordance with the character of line over which the impulses are received.

25. In combination, an impulse receiving 40 relay having two windings, an armature, and a restraining spring for said armature, a spring tension adjusting device, including two field coil windings, for adjusting the tension of said restraining spring, and a battery, said impulsing relay being arranged to receive impulses over lines over a circuit including one conductor of a line, one field coil winding, one winding of said relay, said battery, the other winding of said relay, the other field coil winding, and the other conductor of the line in series in the order

named, said device operating when said field coil windings are energized over said circuit, the extent of operation depending on the sum of the values of the current strength in 55 the two-field coil windings.

26. In combination, an impulse receiving relay having two windings, an armature, and a restraining spring for said armature, a spring tension adjusting device, including two field coil windings, for adjusting the tension of said restraining spring, a battery, said impulsing relay being arranged to receive impulses over lines over a circuit including one conductor of a line, one field 60 coil winding, one winding of said relay, said battery, the other winding of said relay, the other field coil winding, and the other conductor of the line in series in the order named, said device operating when said field coil windings are energized over said circuit, and means for then locking said device operated and for short-circuiting said field coil windings.

27. In an impulse receiving device, an impulse receiving relay, a restraining spring for the armature of said relay, a second relay controlled by said impulse receiving relay, a spring tension adjusting device for adjusting the tension of said spring, means 80 for operating said device in accordance with the current strength of the impulses to be received by said impulse receiving relay, and means controlled by said second relay for locking said device operated and for disabling said operating means.

28. In combination, a relay having a restraining spring for its armature, a spring tension adjusting device for adjusting the tension of said restraining spring operated 90 in the circuit of said relay, the extent of operation depending on the strength of the current in said relay, a second relay controlled by said first relay, and means controlled by said second relay for preventing a 95 retrogression in the operation of said device without interfering with the progression of the operation.

In witness whereof, I hereunto subscribe my name this 17th day of March, A. D. 1926.

RUDOLPH F. STEHLIK.
